UNITED STATES PATENT OFFICE

2,609,800

AUXILIARY PUMP ARRANGEMENT FOR
WATER COOLED ENGINES

Gustav Pielstick, Saint Germain en Laye, France

Application February 8, 1950, Serial No. 143,031
In France February 15, 1949

4 Claims. (Cl. 123—41.47)

1

This invention relates to the installation of auxiliary pumps in diesel engine units.

In high-powered high-speed diesel engines the oil- and water-pumps used for lubricating and cooling the engine absorb a considerable amount of power and are of correspondingly large size. It has been the practice heretofore to mount such pumps as an auxiliary pump group on the engine base frame, all said pumps being driven from a specially-provided shaft extending parallel to the main engine shaft. Because of the large dimensions of the pumps this arrangement has the drawback of making the engine couplings difficult of access through the inspection doors or openings provided therefore.

Diesel engines of the type to which this invention relates generally include banks or lines of cylinders each bank operating a related crank-shaft, and all the crankshafts driving a common speed-converter (reducer or multiplier) gearing.

It is an object of this invention to improve the general arrangement of high-powered diesel engine units of the type described, and more particularly to mount the auxiliary pumps thereof in such a way as to improve accessibility of the engine-couplings reduce the overall dimensions of the diesel plant and do away with the special pump-driving shaft necessary in prior installations.

With the above and further objects in view, my invention essentially consists of mounting the auxiliary pumps in a diesel unit including a plurality of transversely spaced crankshafts driving a common speed-converter (i. e. -reducer or-multiplier) gearing, upon the casing of said gearing. Preferably moreover, the pumps are mounted in at least one line and each line of pumps is driven from a shaft which forms an extension of a timing shaft or camshaft of the engine.

It will be seen that this arrangement will completely clear the inspection doors of the engine frame of any obstruction, and moreover, will substantially reduce the over-all transverse dimension of the diesel plant, as the pumps will now be included within the transverse outer contour of the engine.

According to another feature or advantage of the invention, the usual cooling means fed from the cooling pump or pumps and serving to cool the engine, are also mounted on the speed-converter casing and are directly connected with the related pumps.

Some exemplary forms of embodiment of the invention will now be described with reference

2

to the accompanying diagrammatic drawings, given by way of illustration and not of limitation, and in which:

Fig. 1 is a partial elevation view of an improved diesel plant according to the invention;

Fig. 2 is an end view thereof;

Fig. 3 is an end view of another plant including cooling means mounted in accordance with the invention;

Fig. 4 is a side view of the plant shown in Fig. 3 and

Fig. 5 illustrates the same plant as seen from the other side.

As shown in Figs. 1 and 2, a diesel engine 1 only part of the outline of which is shown comprises two vertically spaced crankshafts 2 and 3 each of which may be driven by a related bank or banks of cylinder and piston units as is now well-known. The crankshafts 2 and 3 are connected through clutch couplings 4 and 5 with corresponding input shafts of a speed-converter gearing unit, generally indicated at 6, and which may be a reducer or a multiplier gearing, depending on requirements. The output shaft of the speed converter is shown at 7.

The illustrative example shown relates to a marine engine, and accordingly three auxiliary pumps have been shown, a brine pump 8 for sea-water, a fresh-water pump 9 and an oil pump 10.

11 indicates a camshaft of the engine and 12 a fuel-intake pipe.

It will be seen that the three auxiliary pumps 8, 9 and 10 are mounted on a side of the casing 35 of the speed-converter gearing 6 and are arranged in line so as to be driven off an extension of the camshaft 11.

In the embodiment of Figs. 3, 4 and 5, the arrangement is generally similar, and corresponding elements have been given similar reference numerals as in Figs. 1 and 2. As shown in Figs. 3 and 4, there are provided on one side of the speed-converter casing 6 a brine pump 8, a fresh-water pump 9 and an oil pump 10 driven from 45 a camshaft 11 of the engine 1, and there is moreover provided a water-cooling unit 13 connected with the water pump and an oil-cooling unit 14 connected with the oil pump, both these cooling units being also mounted on the same side of the speed-converter casing 6 and directly connected with the respectively related pipes as shown at 50 15 and 16.

Fig. 5 shows a similar arrangement of pumps and cooling units on the opposite side of the diesel plant, but associated with the top crank-

shaft 2 rather than with the lower crankshaft 3 thereof. In this case the cooling units 13' and 14' are mounted below rather than above the related pumps 8' and 10'.

It will be understood that the invention is by no means limited to any of the details of embodiment shown in connection with the two constructions selected for exemplification of the invention, and that many modifications may be made therein within the scope of the ensuing claims.

What I claim is:

1. In a diesel plant of the type specified, a multi-crankshaft engine unit, a speed-converter gearing unit aligned with said engine unit to be driven from said crankshafts and having a casing, auxiliary pumps for said engine mounted on said gearing casing on a side thereof and cooling means associated with at least some of said pumps, said cooling means mounted on said gearing casing adjacent to the related pumps and directly connected with said pumps to be driven therefrom.

2. In a diesel plant of the type specified, a multi-crankshaft engine unit including at least an upper crankshaft and at least a lower crankshaft and camshafts associated with said crankshafts, a speed-converter gearing aligned with said engine unit to be driven from the crankshafts thereof and having a casing, a first line of auxiliary pumps for said engine associated with said upper crankshaft mounted on said gearing casing and cooling means mounted on said gearing casing adjacent to and below said pumps and connected therewith to be supplied therefrom, and a second line of auxiliary pumps for said engine associated with said lower crankshaft mounted on said gearing casing and cooling means mounted on said gearing casing adjacent

to and above said related pumps and directly connected therewith to be supplied therefrom.

3. Diesel plant as in claim 2 wherein said first line of auxiliary pumps and associated cooling means are mounted on one side of said gearing casing towards the top thereof and said second line of auxiliary pumps and associated cooling means are mounted on the other side of said gearing casing towards the base thereof.

4. In a diesel plant of the type specified, a multi-crankshaft engine unit comprising related crankshafts and at least one camshaft, a speed-converter gearing unit situated in line with said engine unit, said crankshafts abutting in said speed converter, a casing for said latter and auxiliary pumps for said engine unit mounted on a lateral wall of said gearing casing and being substantially included within the transverse contour of said plant, without projecting outside thereof, and a pump-drive shaft forming an extension of one of said camshafts and driving the pumps in said line.

GUSTAV PIELSTICK.
